REFRIGERATOR CAR CONSTRUCTION

Ralph B. Winship, Montreal, Quebec, Canada, assignor, by mesne assignments, to Standard Railway Refrigerator Company, a corporation of Delaware

Application June 30, 1938, Serial No. 216,732

7 Claims. (Cl. 105—359)

This invention relates to refrigerator cars used to transport perishable commodities at a predetermined temperature. A refrigerator car comprises a body having insulated floor, walls and roof and means for cooling in summer and heating in winter.

This invention applies particularly to cars having the cooling means suspended immediately below the ceiling of the car, said means comprising containers having a refrigerant therein, the refrigerant being pure water ice, ice mixed with salt, a brine solution or frozen brine, known as eutectic ice. It is preferable to provide a flue leading from the space surrounding the container to below the load supporting foraminous floor. The flue, which is preferably adjacent the side wall of the car, provides a path for the circulation of cooled air and also serves to drain off liquid from condensation on the tanks or from melting of the refrigerant.

It is an object of this invention to build a car having bunkers suspended below the ceiling and to provide a drip pan and side flue for circulation of air and draining of liquid.

It is another object of the invention to utilize the space between the vertical side framing members or posts to accommodate the flue, thus decreasing the overall thickness of the wall. The outside width of railway cars is limited to a maximum determined by the tunnel clearances on the railroads on which they operate. The inside width is limited to a minimum determined by the sizes of boxes and crates which are shipped, therefore, with the inside and outside widths severely restricted the thickness of the wall is definitely limited. It is a great advantage, then, to place the side wall flues between the vertical posts so as not to increase the wall thickness.

Another object of the invention is to eliminate the usual side wall diagonal bracing and substitute horizontal belt rails which may be embedded in the insulation, thereby allowing the space between vertical posts free for the flue.

It is a further object of the invention to use a waterproof paper or fabric as the sides of the flue. This decreases both the weight and thickness of the car wall and also facilitates construction since the paper or fabric may be secured to the wall insulation during the manufacture thereof.

Another object of the invention is to construct the refrigerant containers and associated supporting members so that they form a truss extending between the side walls of the car. The

tanks are, therefore, not only partially self-supporting but also help to support the roof of the car.

Another object is to tie the outer roof and ceiling together with metal hatch frames, thus providing a truss-like structure having greater strength and less weight.

It is another object to construct and suspend the refrigerant containers and their supporting members so that one container may be removed for repairs without disturbing either the other containers or the roof of the car.

A further object of the invention is to use the upper parts of the refrigerant containers as the ceiling of the car to support the insulation. This arrangement eliminates both the weight and space which would be required in the use of a separate ceiling.

Another object of the invention is to provide light, strong meat racks, parts of which may be removed without disturbing the remainder of the racks or other parts of the car.

Another object of the invention is to support the refrigerant containers on the underframe by inner frame members, exclusive of the outer sheathing of the car.

It is another object to provide heat radiating pipes under the floor rack and above the floor of the car. These are to be used in cold weather in conjunction with a heater placed preferably underneath the car. The pipes are spaced below the foraminous floor to allow a space therebetween for the movement of circulating air and above the floor to allow for slushing of liquid from refrigerant sometimes placed in the lading compartment of the car.

Another object of the invention is to provide stiffeners for the walls and bottoms of the containers to function as beams between the supporting members of said containers.

It is a further object to arrange said stiffeners to project upwardly inside the container so as not to restrict air flow past the sides and bottom of the containers. A further object in having said stiffeners inside said containers is to provide skids or runners which facilitate movement of ice towards the ends of the containers when the ice is being loaded.

Another object of the invention is to provide means for ventilating the car. Some types of lading do not require refrigeration but require a constant flow of air over them to carry away heat which they constantly emit. This invention provides apertures in the walls of the containers so that when the plug is removed from

the hatch, air may circulate through the hatch and apertures and into the lading space of the car. It is a further object of the invention to provide inverted louvers adjacent said apertures 5 to prevent upwardly splashing liquid from said containers from entering the lading space of the car.

It is a further object of the invention to slope the bottoms of the refrigerant containers down- 10 wardly away from the ventilating apertures, thus reducing the tendency of liquid to splash through the apertures.

Another object of the invention is to provide sheets of moisture-proof paper or fabric in the 15 wall to prevent entrance of water vapor into the insulation, thus impairing the efficiency thereof.

In the drawings:

Fig. 1 is a partial transverse section of the refrigerator car on line 1—1 of Fig. 2.

20 Fig. 2 is a vertical longitudinal section on line 2—2 of Fig. 1.

Fig. 3 is a fragmentary section on line 3—3 of Fig. 2.

25 Fig. 4 is a fragmentary section on line 4—4 of Fig. 2.

Fig. 5 shows a modified construction.

The underframe of the car comprises a center sill 2; cross members (bolsters, cross-bearers and cross-ties) 3 and steel side sill angle 4. A 30 sub-floor 5 and wooden side sill 6 are supported by the underframe of the car; the wooden sill 6 being secured to the steel sill 4 by the bolts 7. Several layers of pliable insulation 8 rest upon the sub-floor 5 and the main load supporting floor 9 is supported by the wooden side sill 6 and the stringer 10 which also serves as a cleat to hold the insulation 8 in place.

The side wall 15 of the car derives its principal support from the Z-bar posts 16 which are 40 riveted to the metallic sub-sill 17. The sub-sill 17 is supported upon and insulated from the underframe of the car by the wooden sill 6. The posts 16 are secured at their upper ends to the inner metallic side plate 18 and braced at intervals along their length by the channel shaped belt rails 19 which are riveted to the posts 16. The side insulation 20 comprises several layers of pliable insulation 21 with a layer of waterproof material 22 secured to one face thereof.

50 The wooden pieces 23 function to further brace the side wall 15 and to hold the insulation 20 in place. The metallic strips 24 and the belt rails 19 also function as cleats to prevent the insulation from slipping. A wooden stringer 25 reinforced by an angle 26 and secured to the metallic sill 4 serves as the lower support for the wood sheathing 27. The upper end of the sheathing 27 is secured to the wooden piece 28 which is tied to the inner metallic side plate 18 by the brackets 29 spaced at intervals longitudinally of the car. The outer metallic side plate 30 is secured to the wooden piece 28.

65 Flues 35 for circulation of air are formed adjacent the wall 15 by placing on the inner side 65 of the Z-bar posts 16 a layer of waterproof material 36. Wooden lining 37 is secured to the posts 16 on top of the paper 36 to resist the side thrust of the lading. Each flue 35 extends longitudinally of the car the distance between the posts 16 and has for its walls the layers of waterproof material 22 and 36. In addition to forming a waterproof flue, this material also serves as a barrier to prevent infiltration of water vapor into the insulation.

70 The refrigerant containers 45 are solid tanks

designed for the retention of the melted refrigerant and are formed from steel plate by welding. The bottom 46 and sides 47—48 of each tank are formed from a single sheet of steel. The ends 49 and top 50 are separate pieces secured preferably by spot welding; the seams being waterproofed by solder or car cement. An opening is provided in the top sheet to communicate with the hatch 51. A plurality of stiffeners 52 are welded to the sides 47, 48 and 10 bottom 46 of the container and extend longitudinally of the container from end to end. The stiffeners 52 function as beams to strengthen the container and as skids upon which the ice may be pushed to the ends of the container. Aper- 15 tures 53 are provided near the tops of the walls 47—48 for the passage of air when it is desired to ventilate the car. Inverted louvers 54 tend through the apertures 53.

A plurality of spaced apart channel shaped carlines 60 extend between and are secured to the inner metallic side plates 18. There are preferably four carlines 60 for each container 45, one positioned on each side of the hatch 51 25 and one near each end of the container. A plurality of transverse bars 61 are secured to the bottom of each container 45. The bars 61 extend a short distance beyond each side of a container and are preferably positioned with one 30 directly below the hatch 51 and one near each end of a container. Each bar 61 is secured preferably by rivets 62 and a gusset plate 63 to a post 16. The bars 61 are preferably channel shaped and have one flange thereof flattened 35 into the plane of the web at each end of the bar to provide adequate space for rivets.

The transverse bar 65 is at the center of a container 45 directly below the hatch 51. A connecting piece 66, preferably angle shaped, connects the bars 65 of directly opposite containers. This is shown in Fig. 1. This construction provides effectively a continuous beam extending between the side posts 16 of the car. Web plates 67—68 are welded to the sides 47—48 45 of the container to stiffen the sides against the outward thrust of the refrigerant and to help support the sides.

Fig. 3 shows the construction at the carline 70 adjacent the hatch 51. A supporting member 71 is riveted to the carline 70 and web plates 72 are welded to the sides 48 of the containers to stiffen the sides and to provide a means to support the containers. The web plates 72 are riveted to the supporting member 71.

Fig. 4 shows the construction near the ends of the containers 45 where the carline 75 and the transverse bars 76 lie in substantially the same vertical plane. The plate 77 functions both to connect the bars 76 of directly opposite containers and to connect said bars to the carline 75. Web plates 78 welded to the sides 48 of the containers function not only to stiffen said walls but to secure the walls 48 to the bars 76 and the plate 77.

The outer roof 80 of the car extends between and is supported by the outer metallic side plates 30. The roof comprises sheets 81 extending transversely of the car and having the transverse edges thereof upturned to form upwardly projecting flanges 82. Inverted channel shaped seam caps, or carlines 83, extending between the outer metallic side plates 30 cover the flanges 82 and are riveted thereto to provide watertight joints. Hatches 51 are provided for the deposit 75

of refrigerant in the containers and are surrounded by hatch frames 85 formed from metallic plates. The roof sheets 81 are provided with upstanding flanges 86 surrounding the 5 hatches 51, said flanges 86 underlying the upper parts 87 of the hatch frames 85. The lower parts of the hatch frames are secured by overlapping pieces 88 to the tops 50 of the containers 45 and to the carlines 60, therefore, the outer 10 roof 80, hatch frames 85, carlines 60 and containers 45 cooperate to form a very strong roof structure. The tops 50 of the containers 45 also function as the ceiling of the car to support the pliable insulation 89. Small sheets 90 support the insulation 89 between containers 45. A 15 layer of waterproof material could be placed above the containers to reduce condensation in the insulation.

The insulated hatch plug 95 comprises a steel 20 shell 96 with insulation 97 inside. A gasket 98 of pliable material is provided to insulate the plug 95 at the line of contact with the hatch frame 85. The gasket 98 also functions as a seal completely around the hatch frame 85 to 25 prevent the entrance of moisture or air.

A pipe 101 is connected to the container 45 at its lowest edge to drain the liquid contents of said 30 container. The pipe leads downwardly through the flue 35 to underneath the floor. A valve 102 is provided at the lower end of the pipe 101 so that the refrigerant may be retained in the container by closing the valve.

A partition or drip pan 105 is provided below 35 each container with an upright wall 106 at the inner edge thereof to provide a central duct 107. The drip pan 105 is connected to the bottom edges of the transverse bars 61 which space the drip pan 105 from the container bottom 46 to provide a 40 passage 108 which communicates with the side wall flues 35. The lading is supported by a foraminous floor comprising spaced apart slats 109 spaced from and supported on the main floor 9 by stringers 110. The air circulates from the 45 lading compartment 111 upwardly through the duct 107, through the passage 108 where it is cooled by contact with the container bottom 46, downwardly through the flue 35, through the space 112 under the foraminous floor and upwardly between the slats 109 to the lading compartment 111 where it is warmed by contact with 50 the lading.

In transporting perishable commodities in winter it is often necessary to supply heat to prevent them from freezing. Heat radiating pipes 115 are provided under the foraminous floor. These 55 pipes 115 are designed to carry a liquid which is heated by a heater preferably suspended underneath the floor of the car. The pipes 115 are spaced below the slats 109 so as not to interfere 60 with the circulation of air through the spaces between the slats 109. The pipes are also spaced from the main floor 9 so as not to prevent the slushing of water deposited there by the melting of ice packed with the lading or by other means.

65 Refrigerator cars are often used to transport meat. When used for this purpose they must be provided with racks from which the meat can be suspended. Horizontally extending channel shaped members 120 secured to the side posts 16 support the outside ends of a series of parallel 70 pipes 121. The inner ends of the pipes 121 are supported by a longitudinally extending inverted channel shaped member 122 suspended by rods 123 from the connecting pieces 66 and the plates 75 177. Longitudinally extending wooden beams 124

from which meat is suspended have holes through which the pipes 121 pass; the pipes 121 serving to support the beams 124. Plugs 125 held in place by keys 126 through the pipes 121 allow the rack to be removed by removing the keys 126 and sliding the plugs 125 into the pipes 121. The pipes extend only from the members 120 to the central member 122, thus allowing one side of the rack to be removed without disturbing the other side.

The refrigerant containers, supporting members therefor and portions of the roof structure all cooperate to form a supporting structure for the containers. Near the end of each container, the transverse bars 76 and the plate 77 are connected together to form, in effect, a lower carline 15 member disposed below the containers 45. Said lower carline member and the upper carline 75 20 are tied together by the plate 77 and the containers 45, particularly the ends 49 and sides 47-48 thereof, thereby forming a container supporting structure between the side walls 15 of the car.

Near the center of the containers 45, upper carlines 10 are disposed on each side of the hatch 51. The transverse bars 65 are connected together at 25 the center of the car by the connecting piece 66 to form, in effect, a lower carline member disposed below the containers 45 and in a vertical plane disposed between the vertical planes through the upper carlines 10. The container walls 47-48 30 are secured to the lower carline member by the web plates 67-68, respectively, and the walls 48 are connected to the upper carlines 10 by the web plates 12. The containers 45, the walls 48 in particular and the walls 47, to a limited extent, thereby form a tie between the upper and lower carlines and provide cooperation therebetween to 35 support the containers.

The refrigerant containers are constructed and supported so that any container may be removed 40 without disturbing other containers or the roof structure. After the drip pan has been removed all rivets are readily accessible.

The drawings show the ventilating apertures 53 near the tops of the walls 47-48. They would be 45 most effective if placed in the wall 48 as the ventilating air could flow through the apertures 53 and downwardly through the central duct 107 to the lading compartment 111. Air passing through the apertures 53 into the channel 113 must flow 50 downwardly through the flues 35, under the foraminous floor and upwardly to the lading compartment 111.

Fig. 5 shows a modified form of ventilating apertures. The apertures 130 are positioned near 55 the tops of the walls 48. Baffle plates 131 are spaced from the walls 48 a short distance to allow air to pass through the apertures 130. Liquid which splashes through the apertures is prevented by the plates 131 from entering the central duct 107 and damaging the lading in the space 60 below the duct 107.

The accompanying drawings illustrate the preferred form of the invention, though it is to be understood that the invention is not limited to the 65 exact details of construction shown and described, as it is obvious that various modifications thereof, within the scope of the claims, will occur to persons skilled in the art.

I claim:

1. In a refrigerator car having a roof and spaced apart walls, a refrigerant container below the roof, and means associated with said container to provide a support therefor, said means comprising upper and lower carline members ex- 75

tending between and secured to said car walls, attaching means securing one of the walls of said refrigerant container to said upper carline member, and attaching means independent of said 5 first mentioned attaching means securing said container wall to said lower carline member.

2. In a refrigerator car having a roof and spaced apart walls, a refrigerant container below the roof and adjacent each of said car walls, and 10 means associated with said containers to provide a support therefor, said means comprising upper and lower carline members extending between and secured to said car walls, attaching means securing the adjacent walls of said refrigerant 15 containers to said upper carline member, and attaching means independent of said first mentioned attaching means securing said container walls to said lower carline member.

3. In a refrigerator car having a roof and 20 spaced apart walls, a refrigerant container below the roof and adjacent each of said car walls, and means associated with said containers to provide a support therefor, said means comprising an upper carline member extending between and secured to said car walls, a lower carline member below said container extending between and secured to said car walls, said lower carline member comprising a transverse bar secured to the 25 bottom of each of said containers and means to connect the adjacent ends of said bars, attaching means securing the adjacent walls of said refrigerant containers to said upper carline member, and attaching means independent of said 30 first mentioned attaching means securing said container walls to said lower carline member.

4. In a refrigerator car having a roof and 35 spaced apart walls, a refrigerant container below the roof, and means associated with said container to provide a support therefor, said means comprising spaced apart upper carline members 40 above said container extending between and secured to said car walls, spaced apart lower carline members below said container extending between and secured to said car walls, said upper and lower carline members being disposed in spaced apart vertical planes, attaching means securing one of the walls of said refrigerant container to 45 said upper carline members, and attaching means

independent of said first mentioned attaching means securing said container wall to said lower carline members.

5. In a refrigerator car having a roof and spaced apart walls, a refrigerant container below 5 the roof, and means associated with said container to provide a support therefor, said means comprising spaced apart upper carline members above said container extending between and secured to said car walls, a lower carline member below said container extending between and secured to said car walls, said lower carline member being disposed in a vertical plane between the vertical planes of said upper carline members, attaching means securing one of the walls of said 10 refrigerant container to said upper carline members, and attaching means independent of said 15 first mentioned attaching means securing said container wall to said lower carline member.

6. In a refrigerator car having a roof and 20 spaced apart walls, a refrigerant container below the roof, and means associated with said container to provide a support therefor, said means comprising an upper carline member above said 25 container extending between and secured to said car walls, spaced apart lower carline members below said container extending between and secured to said car walls, said upper carline member being disposed in a vertical plane between the 30 vertical planes of said lower carline members, attaching means securing one of the walls of said refrigerant container to said upper carline member, and attaching means independent of said 35 first mentioned attaching means securing said container wall to said lower carline member.

7. In a refrigerator car having a roof and spaced apart walls, a refrigerant container below the roof, and means associated with said container to provide a support therefor, said means comprising an upper carline member extending 40 between and secured to said car walls, a lower carline member extending between and secured to said car walls and secured to the bottom of said container, and attaching means securing one 45 of the walls of said refrigerant container to said upper carline member.

RALPH B. WINSHIP.
